PANEL.

No. 20,367.

Patented Dec. 9, 1890.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,367, dated December 9, 1890.

Application filed November 12, 1889. Serial No. 320,081. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

Said design relates to an ornamental configuration of the surface of the panel. Upon said panel is a raised circular elevation A. At the center of said elevation is a circular por-

tion B, and extending tangential to the surface of said circular portion B to the periphery of the circular elevation A are grooves 15 or channels C. The number of these channels is not material.

I claim as my invention—

The design for an ornamental panel, substantially as herein shown and described.

ALLAN B. CAMERON.
